(57) **CLAIM**

The ornamental design for a bar code reader as shown and described.

DESCRIPTION

FIG. 1 is a top, front, right perspective view of a bar code reader showing my new design.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The broken lines in the drawings illustrate portions of the bar code reader that form no part of the claimed design.
